UNITED STATES PATENT OFFICE.

GEORGE B. MARX, OF NEW YORK, N. Y.

EXTENSION-BODY FOR TRUCKS, &c.

1,106,104.

Specification of Letters Patent.

Patented Aug. 4, 1914.

Application filed June 11, 1913. Serial No. 772,977.

To all whom it may concern:

Be it known that I, GEORGE B. MARX, a citizen of the United States, residing in the borough of Manhattan of the city of New York, in the county of New York, in the State of New York, have invented certain new and useful Improvements in Extension-Bodies for Trucks, &c., of which the following is a specification, reference being had to the accompanying drawings, which form a part hereof.

This invention relates to the construction of bodies for wagons or trucks, either motor-propelled or horse-drawn, cars, etc., which must be lengthened or shortened according to the length of the load, such as lumber, timbers, structural steel, etc., to be carried. The object of the invention is to produce a very strong extension body which can yet be manipulated easily. In the attainment of this object the longitudinal members of the frame or body are formed of telescoping tubes and suitable provisions are made for securing such tubes to the front and rear trucks or truck members, for reinforcing the longitudinal members when the frame or body is extended, and for facilitating the extension of the body.

The invention will be more fully explained hereinafter with reference to the accompanying drawings in which it is illustrated and in which—

Figure 1 is a view in longitudinal section on the plane indicated by the broken line 1—1 of Fig. 2, of a truck or wagon which is constructed in accordance with the invention. Fig. 2 is a top view of the parts shown in Fig. 1, the middle longitudinal member being shown in section. Figs. 3, 4 and 5 are detail views in transverse section, and on a somewhat larger scale, on the planes indicated by the broken lines 3—3, 4—4 and 5—5 respectively of Fig. 1. Fig. 6 is a detail view, also on a larger scale and partly in longitudinal section, illustrating particularly the construction of the longitudinal, extensible members. Figs. 7 and 8 are detail views in side elevation and plan respectively, illustrating particularly the devices concerned with the drawing of the reinforcing tube into position when the body is extended.

The present improvements are concerned wholly with the extensible body or frame and do not involve directly the construction of the front and rear trucks, which may

therefore be of any desired or suitable construction. As indicated in the drawing the front truck comprises as usual wheels *a*, an axle *a'*, springs *a''*, and a frame *a'''* with its wear-plate *a''''*. Upon the wear-plate *a''''* rests a similar wear-plate *b* which is secured to cross bars *b'*. This frame may also be provided with a plate *b''* for the reception of the usual king-pin *b''''*. The rear truck, as indicated in the drawings, may also comprise wheels *c*, an axle *c'*, springs *c''*, cross bars *c'''* and *c''''*, and braces *c''''*.

Each longitudinal member of the frame or body consists of an internal tube *d* which is firmly secured at its forward end to the forward truck frame, or rather to the cross bars *b'*, as by suitable bolts *d'*; an external tube *e*, which telescopes upon the internal tube *d* and is firmly secured at its rear end to the rear truck, as by suitable yoke bolts *e'*; and an external reinforcing sleeve or tube *f* which surrounds and is movable upon the tube *e*. The forward portion of the tube *e* is slotted on its underside, as at *e''*, to straddle the bolts *d'* and the blocks *d''* which may be interposed between each cross bar *b'* and each tube *e*.

Longitudinal girders *g* are secured at their rear ends to the rear truck and, when the body is shortened, rest at their forward ends upon the cross bars *b'*.

Bars *h* are secured at their forward ends to the cross bars *d'* and pass through guides *i* secured to a cross bar *i*, which is secured to the girders *g* and to the outer tubes *e*, and may be provided at intervals with holes *i''* for engagement by screw pins *k*, to hold the members of the frame in adjusted position. The bars *h* may pass through similar guides *c''* on the cross bar *c''''*, which guides may also be provided with screw pins *k*.

The reinforcing tubes or sleeves *f* are united, so as to be moved together, by a bar *l*, provided with straps *l'* and resting upon guide bars *m* which may be suitably secured to the under sides of the girders *g*. When the body is extended, so that the outer tubes *e* are drawn back over the inner tubes *d*, so that their slotted portions stand between the rear cross bar *b'* and the cross bar *i*, the reinforcing tubes or sleeves *f* are placed so as to cover the slotted portions of the tubes *e*. The necessary movement of the tubes *f* might be effected by a separate manipulation, but provision is made, in the construction shown in the drawings, where-

by, as the frame or body is extended, the reinforcing tubes *f* are moved relatively to the outer tubes *e*. As shown latches *n* are pivoted upon the ends of one of the cross bars 5 *U* and are adapted to engage the ends of the cross bar *l*, so that when the forward truck is moved forward with respect to the rear truck, the reinforcing sleeves *f* are also moved forward with it so as to cover the 10 slotted ends of the outer tubes *e*. As the body may be extended more than the length of the reinforcing sleeves, it is desirable that provisions be made whereby the slotted ends of the tubes *e* shall not be withdrawn 15 from the reinforcing sleeves *f*. Accordingly the latches *n* should be disengaged from the bar *l* before the slotted ends of the tubes *e* are withdrawn from the reinforcing sleeves *f*. For this purpose supports *o* are secured 20 to the girders *g* and are provided with cam-like ends *o'* which, when the proper displacement of the reinforcing sleeves has been attained, lift the latches from engagement with the bar *l*, the hooked ends of the latches 25 being supported by the supports *o* during the further forward movement of the forward truck with respect to the girders *f*.

It will be understood that various changes in details of construction and arrangement 30 may be made without departing from the spirit of the invention.

I claim as my invention:—

1. An extensible body for trucks, etc., having telescoping longitudinal members secured respectively to the forward and rear portions of the body, means to reinforce said members when the truck or body is extended, and means carried by one portion of the body and in operative engagement with said 35 reinforcing means to position automatically said reinforcing means with respect to said members when the body is extended.

2. An extensible body for trucks, etc., having telescoping longitudinal tubes secured 40 respectively to the forward and rear por-

tions of the body and sleeves surrounding the tubes to reinforce the same when the body is extended, latches secured to one portion of the body and in operative engagement with the sleeves to maintain their position with respect to the last named portion of the body when the body is extended, and means carried by a relatively movable portion of the body to disengage automatically the latches from the sleeves at a pre- 50 determined point.

3. An extensible body for trucks, etc., having telescoping longitudinal tubes, means to secure the tubes respectively to the forward and rear portions of the body and blocks 60 through which the securing means for the inner tubes pass interposed between the inner tubes and the portion of the body to which said inner tubes are secured, the outer tubes being slotted to straddle said blocks 65 to permit the complete telescoping of the tubes.

4. An extensible body for trucks, etc., having telescoping longitudinal tubes, means to secure the tubes respectively to the forward 70 and rear portions of the body, the outer tubes being slotted to embrace the securing means for the inner tubes and sleeves surrounding the outer tubes to embrace and reinforce the slotted portions thereof when 75 the body is extended.

5. An extensible body for trucks, etc., having tubular telescoping reach members secured respectively to the forward and rear portions of the body, independent longitudinal girders secured at one end to one portion of the body and adapted to have their free ends rest on the other portion of the body when the body is shortened.

This specification signed and witnessed 85 this ninth day of June A. D., 1913.

GEORGE B. MARX.
